UNITED STATES PATENT OFFICE.

DOMINGO MOTTA, OF GENOA, ITALY, ASSIGNOR OF TWO-THIRDS TO EDOARDO RUGIU
AND ANTONIO VILLAIN, BOTH OF GENOA, ITALY.

STEREOTYPE FOR CHALCOGRAPHIC, TYPOGRAPHIC, AND LITHOGRAPHIC REPRODUCTION.

1,331,119.

Specification of Letters Patent.

Patented Feb. 17, 1920.

No Drawing.

Application filed February 8, 1919. Serial No. 275,870.

To all whom it may concern:

Be it known that I, DOMINGO MOTTA, subject of the King of Italy, residing at Genoa, Italy, have invented certain new and useful 5 Improvements in and Relating to Stereotypes for Chalcographic, Typographic, and Lithographic Reproduction, of which the following is a specification.

The object of the present invention is to 10 obtain stereotype plates or blocks for printing in the simplest possible manner both as regards the material (in place of copper, zinc, lithographic stone or the like) and the artistic or industrial manipulation and the 15 process of printing.

The problem has been solved and realized practically by means of a special composition which when spread on paper or other supporting substance is grained or rolled 20 and should then present the following properties:

1. The dimensions varying as desired;
2. Presenting a surface suitable for drawing or tracing a design thereon;
- 25 3. Being of sufficient thickness to enable the surface to be easily engraved by means of a metal point or hard crayon;
4. Being of sufficient ductability to enable fine or thick lines or cross-hatched lines to

30 be drawn thereon without any interstices or confusion of lines.

5. Being adapted to typo-photographic, photo-lithographic and photo-engraving processes;

35 6. Being incombustible and insoluble either in water, alkalis or acids, and resistant to the friction of pullin.

The special composition is composed of 40 carbonate of chalk, silicates of magnesia and as agglutinant.

By way of example, the composition for applying to paper or other support for chalcographic and typographic stereotypes is the following:—

45 Carbonate of lime and silicate or silicates of magnesia in equal parts. These substances are suitably dissolved and agglutinated with a gum of the consistency of syrup, preferably of an organic nature, but 50 this is not essential.

Paper prepared according to the present invention and intended for chalcographic reproductions has a smooth surface and is lightly engraved with a hard crayon or with

a metal point and treated with a solution of 55 an ordinary spirit varnish for the purpose of hardening the surface and for insulating the chalcographic ink.

A chalcographic stereotype replacing those of copper or zinc or others in use at 60 the present time can thus be obtained.

Paper prepared according to the present invention and intended to be used for typographic reproductions can have the surface either reticulated, grained or smooth. 65

To obtain typographic stereotypes not necessitating depth of line in the engraving, the paper or other supporting fabric can have a network or grain in relief on a base block having care that the height of the network 70 or grain is equal to that of the base block so that the instrument will engrave traversing only the said grain or net work.

The design thus obtained can be utilized 75 as a stereotype for rotary typographic machines by attaching it on to the blank when the latter has received the imprint of the characters.

For platen typographic machines it is necessary to cast the stereotype which is effected by inclosing the design executed on the paper in a stereotype mold and afterward casting the lead as usual.

Paper prepared with a smooth surface in accordance with this invention and intended 85 for typographic reproductions will be engraved as has already been mentioned in taking care to lower the wide white margins by employing the extra sheets as usual. After this it can be used direct for rotary machines and after casting in a stereotypic 90 mold, for platen machines.

Paper prepared according to the present invention and intended to serve for lithographic reproductions should be rendered 95 insoluble by means of formaline, for instance. This paper has a smooth or slightly grained surface and is employed as usual with ink or lithographic chalk or similar means.

The typo-litho-chalcographic papers are subjected to all the usual manipulations and treated in the ordinary manner.

What I claim is:—

1. A stereotype plate comprising a base 105 sheet and a surface coating on said base sheet, said coating comprising carbonate of lime and silicates of magnesia in substan-

tially equal proportions, dissolved and agglutinated with a gum.

2. A stereotype plate comprising a base sheet having a network or grain in relief, 5 and a surface coating on said base sheet, said coating comprising carbonate of lime and silicates of magnesia in substantially equal proportions, dissolved and agglutinated with a gum.

10 3. A stereotype plate comprising a paper base sheet, and a surface coating on said

base sheet, said coating comprising carbonate of lime and silicates of magnesia in substantially equal proportions, dissolved and agglutinated with a gum.

15

In testimony whereof I affix my signature in presence of two witnesses.

DOMINGO MOTTA.

Witnesses:

CARBONE VINCENZO,
WILLIAM P. SHOCKLEY.
